CLAIM

The ornamental design for a package for skin care products as shown and described.

DESCRIPTION

FIG. 1 is a perspective view the package for skin care products showing our new design;

FIG. 2 is a front elevation view thereof;

FIG. 3 is a rear elevation view thereof;

FIG. 4 is a right-side elevation view thereof, the left-side elevation view being a mirror image thereof;

FIG. 5 is a top plan view thereof; and,

FIG. 6 is a bottom plan view thereof.

The broken dash lines shown in the drawing views illustrate portions of the package for skin care products that form no part of the claimed design. The stipple pattern shown in the drawing views represents contrasting color.
